UNITED STATES PATENT OFFICE.

HERBERT D. ALLEE, OF DETROIT, MICHIGAN.

METHOD OF MAKING SCREENS.

Application filed March 15, 1926. Serial No. 94,975.

The invention relates to screens and has among its objects the provision of a simply constructed durable and cheaply manufactured screen.

5 A further feature of the invention resides in providing a method of making a plurality of screens affording less expensive production. Thus, with my invention, a plurality of screens may be constructed, opposite border frames being provided to make up a number of screens connected integrally as by the screen material. By thus building up a plurality of screens, the separate screens may be severed from each other by a simple cutting 15 operation.

With these and other objects in view, the invention resides in the novel features of construction and combination and arrangements of parts as more fully hereinafter described 20 and claimed.

Referring to the accompanying drawings in which like reference characters indicate corresponding parts:

Figure 1 represents the initial step in the 25 manufacture of the screens;

Figure 2 is a perspective view showing one of the side border frame bars;

Figure 3 is a sectional view along 3—3 of Figure 2;

30 Figure 4 is a fragmentary view in cross section illustrating the application of the side border frame bars to the screen material;

Figure 5 is a view corresponding to Figure 1 with the side border frame bars applied 35 to the screen material;

Figure 6 is a detail sectional view along 6—6 of Figure 5 showing a side border frame bar in clamped engagement with the screen material;

40 Figure 7 is a fragmentary perspective view illustrating the next step in the manufacture of the screens including mitering the side frame bars;

Figure 8 is a plan view showing a trans- 45 verse border frame bar;

Figure 9 is a fragmentary view showing the transverse frame bars applied to the screen material;

50 Figures 10, 11 and 12 are sectional views along 10—10, 11—11 and 12—12 respectively of Figure 9;

Figure 13 is a perspective view illustrating the final step in the process consisting of severing the finished screens, and

Figure 14 is a plan view illustrating a completed screen.

In the drawings reference character A represents a table or like support over which is extended a strip of screen material B. For convenience, the screen material may be unwound from a roll of screen material C which may be supported by suitable brackets 10 from the table A. The strip of material B has a width substantially corresponding to one dimension of the finished screen product and the initial step in the method consists in extending this strip of material over the table A for a length of twenty or thirty feet for example, depending upon the number of screens to be made at a time.

The next step in the operation consists in providing a pair of substantially U-shaped sheet metal, side border frame bars D, which, as shown in Figures 2 and 3, particularly, are slotted transversely at 11, and mitered, 50 the spacing of these slotted formed portions substantially corresponding to the other desired final dimension of the screen. The projections 12 preferably have their ends return-bent at 13 and spaced apart sufficiently 55 to freely receive the screen material B therebetween. As shown in Figure 3, the slots 11 preferably extend along the projections 12 as far as the inner extremities of the return-bent portions 13. As shown in Figures 4 and 5 these side border frame bars D are moved inwardly toward each other so as to engage 60 the opposite longitudinal edges of the strip of screen material B between the projections 12.

The next step in the operation consists in moving together the projecting ends 12 of the frame bars D so as to clamp therebetween the screen material. This may be accomplished in any suitable manner such as by 65 running rollers or other tools longitudinally along the inner extremities of the frame bars D.

Before the frame bars D are applied to the screen material I prefer to miter the portions 100 of the frame bars D adjacent the slot 11 as shown at 14 in Figure 7, although when found more convenient, the mitering may be done after application of these frame bars to the screen material. The frame bars D may then 105 be positively secured to the screen material, as by spot welding at suitable points 15.

For bordering the remaining opposed sides

to complete the screens I have provided a pair of complementary transverse border frame bars 16 and 17 which, as shown in Figure 12, 5 may have their longitudinal edges return-bent, the elements 16 and 17, together forming substantially U-shaped border frames corresponding to the U-shaped side border frame bars D. As shown in Figure 8, the ends of the frame bars or elements 16 are mitered at 10 18 to conform with the mitered portions 14. The next step in the operation consists in placing the transverse frame elements 16 and 17 at opposite sides of the screen material re-spectively so as to engage therebetween the 15 screen material with the ends of these elements in face contact with the mitered portions 14. By reason of such construction the frame members on opposite sides of the screen material are brought to lie substantially in a 20 common plane.

The transverse frame elements 16 and 17 may then be welded to each other and to the screen material by spot welding at suitable points 19. Also the corner construction may 25 be spot welded as indicated at 20.

At this point in the method of manufacturing the screens it will be noted that a plurality of screens have been formed, integrally connected by the continuous strip of screen 30 material B and also by the portion 21 of the side frame bars D at the extremities of the slots 11.

The final step in the method may consist in severing the screens from each other and this 35 may be conveniently accomplished by severing means such as the blade 22 pivotally supported at 23 or otherwise suitably guided along the edge of table A. The finished connected screens are thus moved along the table 40 until the slots 11 register with the path of movement of blade 22, at which time the end screen may be severed by the blade and the next screen moved into severing position as will be readily understood. In Figure 14 I 45 have illustrated the finished screen. It will be apparent that after the last screen has been severed the strip of screen material will have again been moved over table A from the roll of material C ready for the next series of operations in making up another set or series of 50 screens.

It should be understood that my improved screen may, if desired, be constructed by other methods of manufacture than that described 55 above. It must also be apparent that if desired, the various steps of manufacture such as I have outlined for purposes of illustration may be followed in other than the particular sequence that I have described.

60 While it is believed that from the foregoing description, the nature and advantage of my invention will be readily understood, I desire to have it understood that I do not limit myself to what is herein shown and 65 described and that such changes may be re-

sorted to when desired as fall within the scope of the claims.

What I claim as my invention is:—

1. The method of manufacturing screens 70 consisting in providing a strip of screen material sufficient for a plurality of screens of the final desired dimension, applying border frame members to said strip of material and finally severing the strip to form a plurality of screens. 75

2. The method of manufacturing screens 80 consisting in providing a body of screen material, applying border frame members to a portion of said material and finally severing the screen from the main body of the material. 85

3. The method of manufacturing substantially rectangular screens consisting in providing a strip of screen material sufficient for a plurality of screens of the final desired dimensions, applying a border frame along the longitudinal edges of said material and transversely of the material, the spacing of the transverse border frames corresponding to one desired dimension of the screen and finally severing the strip of screen material by 90 cutting the same transversely at the said transverse border frames to form a plurality of screens. 95

4. The method of manufacturing substantially rectangular screens consisting in providing a strip of screen material sufficient for a plurality of screens of the final desired dimensions, the width of the strip corresponding substantially to one desired dimension of the finished screens, applying a border frame along the opposed longitudinal edges of the strip and transversely of the strip of material at a plurality of points along its length spaced to correspond substantially to the other desired dimension of the screens securing the border frames to the screens, and finally cutting the strip transversely to form a plurality of finished screens. 100 105

5. The method of manufacturing substantially rectangular screens consisting in providing a strip of screen material sufficient for a plurality of screens of the final desired dimensions, the width of the strip corresponding substantially to one desired dimension of the finished screens, applying a border frame 110 along the opposed longitudinal edges of the strip and transversely of the strip of material at a plurality of points along its length spaced to correspond substantially to the desired dimension of the screen securing the border frames to the screens, feeding the strip intermittently and cutting the strip transversely at periods of rest of the strip to sever the completed screens. 115 120

6. The method of manufacturing screens 125 which consists in inserting the longitudinal edges of a length of screen material in pre-formed border members, arranging cross members on opposite sides of the screen material, transversely thereof and at a plurality 130

of longitudinally spaced points, securing the cross members to the screen material and to each other, and subsequently cutting the length of screen material adjacent the cross members to form a plurality of screens.

7. The method of manufacturing screens which consists in preforming a pair of longitudinal border members, inserting the longitudinal edges of a length of screen material 10 in the preformed border members, securing the border members to the said screen material, transversely slotting the border members at a plurality of predetermined points, preforming a plurality of transverse frame 15 members, mounting these transverse frame members transversely of the screen material and at opposite sides thereof adjacent the slots in the border members, securing the transverse frame members to the screen material 20 and to each other, and subsequently cutting the screen material adjacent the transverse frame members to form a plurality of individual screens.

8. A step in the process of manufacturing 25 screens, which consists in applying transverse frame members to the opposite sides of a length of screen material, securing opposed pairs of these transverse frame members to the screen material and to each other and 30 severing the length of screen material adjacent the said transverse members.

9. The method of manufacturing screens 35 which consists in applying a border to a length of screen material, applying a plurality of transverse members to the length of screen material, and subsequently severing

the length of screen material adjacent the said transverse members.

10. The method of manufacturing screens which consists in preforming a pair of border 40 members, inserting the longitudinal edges of a length of screen material in the preformed border members, slotting the border members at a plurality of predetermined points, mitering the border members adjacent the said 45 slots, preforming a plurality of transverse border members, arranging these transverse border members in pairs transversely of the screen and on opposite sides thereof, and with their ends in engagement with the mitered 50 portions of the longitudinal border members, and subsequently severing the length of screen material between each pair of transverse border members.

11. The method of manufacturing screens, 55 which consists in securing to a length of screen material longitudinal and transverse border members to form a plurality of individual screens joined to each other by means of intermediate portions of the screen material and subsequently transversely cutting the intermediate portions of the screen material to free the individual screens.

12. A step in the manufacture of screens 60 which consists in securing to a length of screen material and intermediate the ends thereof a plurality of transverse border members in spaced relation to each other longitudinally of the length of screen material.

In testimony whereof I affix my signature.

HERBERT D. ALLEE.
